2,586,083

FOUNTAIN SPIGOT

Richard F. Poultnay, Pomeroy, Wash.

Application January 24, 1950, Serial No. 140,273

3 Claims. (Cl. 299—10)

1

My invention relates to improvements in spigots.

A primary object of my invention is to provide a spigot for sinks, washstands and the like, and including a swiveled spout or nozzle which may be directed upwardly to form a drinking fountain, or downwardly for conventional usage.

A further object is to provide a spigot of the above-mentioned character having novel means to prevent the spigot from being turned on, except when the spout or nozzle of the spigot is turned fully upwardly or fully downwardly.

Accordingly, it is another object of the invention to provide a spigot including a swiveled spout which may be turned only when the spigot is completely turned off or closed.

A further object is to provide a spigot of the above-mentioned character which is highly simplified and compact in construction, extremely strong and durable, and very easy to manipulate.

Other objects and advantages of the invention will be apparent during the course of the following description.

In the accompanying drawings forming a part of this application, and in which like numerals are employed to designate like parts throughout the same:

Figure 1 is a central, vertical, longitudinal, sectional view through a spigot embodying my invention, parts broken away;

Figure 2 is an enlarged, fragmentary, central, vertical section through the spigot, and showing parts thereof arranged in different operative positions from their positions of Figure 1, part in elevation;

Figure 3 is an enlarged transverse vertical section taken on line 3—3 of Figure 1;

Figure 4 is a similar sectional view taken on line 4—4 of Figure 1;

Figure 5 is an enlarged perspective view of a sleeve removed, part in section; and

Figure 6 is an enlarged, fragmentary, side elevational view of a valve stem removed.

In the drawings, where, for the purpose of illustration, is shown a preferred embodiment of my invention, the numeral 10 designates a stand pipe of a spigot which includes an upright valve body or casing 11 screw-threaded at its upper end, as shown at 12, for the reception of the usual packing nut, not shown. The bottom of the valve body 11 is provided with a flat, radial flange 13 adapted to be seated upon the top of a wash basin or the like. The upper end of the valve body 11 is provided with an internally screw-threaded bore 14 for receiving therein the

2

usual screw-threaded valve stem or actuator 15 including a top reduced extension or shaft 16 to which the usual handle, not shown, is secured. The screw-threaded bore 14 leads into a central, enlarged, internal recess 17 forming a chamber, and the bottom side of the recess 17 is provided with a shallow counterbore 18 which leads into a reduced bore or passage 19, in turn leading to the bore of the stand pipe 10. The bottom of the counterbore 18 is provided with an annular valve seat 20 surrounding the reduced bore 19, and the usual flat washer 21 is secured by means of a screw 22 or the like to the bottom end of the screw-threaded valve stem 15. When the stem 15 is turned for completely shutting off or closing the spigot, the washer 21 will be seated upon the annular valve seat 20. The construction thus far described is conventional and well known.

The valve body or casing 11 further comprises an integral, laterally extending projection or boss 23 having a flat, outer end face 24. The boss 23 is provided in its outer end 24 with a large, screw-threaded recess 25 leading into the recess or chamber 17 and having a flat, inner end 26 parallel with the outer end 24 and with the axis of the valve stem 15.

An annular, screw-threaded ring or sleeve 27 is mounted within the screw-threaded recess 25, and seated upon a suitable lock washer 28 which engages the inner end or bottom 26 of the recess. The ring or sleeve 27 is provided at its outer end with a radially inwardly projecting, annular flange or extension 29 flush in assembly with the outer end 24.

A swiveled spout or nozzle 30 is provided, and this spout 30 is elongated and preferably conically tapered, as shown, and formed at its free or outer end to provide a short, transverse or lateral discharge extension 31 having its axis disposed at right angles to the passage or bore 32 of the spout. The spout or nozzle 30 has a flat, inner end or face 33 for sliding engagement against the outer end 24. The diameter of the end 23 is preferably the same as the diameter of the outer end 24 of boss 23, as shown. The spout 30 is provided in its inner end 33 with a central, axial, screw-threaded recess 34 receiving therein an elongated bearing sleeve 35, the bearing sleeve being externally screw-threaded at its outer end, as shown at 36, for engagement within the recess 34. The outer end of the bearing sleeve 35 is seated against a lock washer 37 which is mounted within the bottom of the screw-threaded recess 34. The bore 38 of the bearing sleeve 35 communicates directly with the bore or passage 32

and chamber or recess 17, as shown. The bearing sleeve 35 is thus adapted to rotate with the nozzle or spout 30, and the bearing sleeve extends through the bore of the ring or sleeve 27 and is provided at its innermost end with an integral, radially projecting, annular flange 39. The outside diameter of the annular flange 39 is slightly smaller than the inside diameter of the lock washer 28, as shown. The outer side or face 40 of the flange 39 is inclined or beveled, as is the inner side or face 41 of the annular flange 29, so that a continuous annular passage or space is provided between the periphery of the bearing sleeve 35 and bore of the ring 27, and this annular passage extends between the beveled faces 40 and 41, as shown.

Suitable thin, metal washers 42 are seated against the faces 40 and 41, and disposed within the annular passage between the bearing sleeve 35 and ring 27. A tubular, lubricating seal or washer 43 is provided, and mounted within the passage between the bearing sleeve 35 and ring 27. The opposite ends of the lubricating seal 43 are beveled, as shown, for engagement with the metallic washers 42. The element 43 is preferably formed of semi-hard rubber or synthetic rubber preferably impregnated with fine graphite or some other suitable solid lubricant. The arrangement is such that the ring 27 is held firmly against rotation within the boss 23, while the spout 30 and bearing sleeve 35 are held against relative rotation, but are freely rotatable as a unit within the ring 27 and associated elements. Obviously, the arrangement of the flanges 29 and 39 and associated elements prevents end or axial play in the spout 30. Suitable screw driver slots or the like may be provided in the outer end of the ring 27, as shown at 44.

Novel means are provided which make it impossible to turn the spigot on except when the discharge extension 31 is directed fully upwardly or fully downwardly. These means likewise make it impossible to turn the spout 30 from one position to another, except when the spigot is completely turned off, and the washer 21 is seated upon the seat 20. Such means comprises a circularly curved or arcuate groove 45 formed in the inner end of the bearing sleeve 35 and concentric with the axis of rotation of the spout 30 and bearing sleeve. The arcuate groove 45 extends circumferentially for 180° about the inner end of the bearing sleeve 35, as shown. The arrangement is such that the groove 45 is relatively shallow at its longitudinal center, as shown at 46, and relatively deep at its opposite ends 47. The bottom of the groove 45 is smooth and gradually inclined from the relatively deep ends 47 toward the central shallow portion 46 of the groove, Figure 5. The valve body 16 is provided in the bottom 26 of screw-threaded recess 25 with a small, transverse opening or bore 48 extending parallel to the longitudinal axis of rotation of the bearing sleeve 35 and intersecting the groove 45. The inner end of the bore 48 leads into a reduced opening or bore 49, in turn leading into or intersecting the screw-threaded bore 14. Mounted within the bores 48 and 49 for reciprocation is an axially shiftable pin 50 including an integral collar or washer 51 which is slidable within the bore 48. A compressible coil spring 52 surrounds the pin 50 between the collar 51 thereof and the inner end or bottom of the bore 48, as shown in Figure 2. This spring 52 serves to constantly urge the pin 51 toward the bearing sleeve 35, and the outer end of the pin constant-

ly engages within the arcuate groove 45 of the bearing sleeve. The screw-thread of the valve stem 15 is provided at one point only with a radial notch or detent 53 adapted to receive the inner end of the pin 50 when the spigot is completely turned off and the washer 21 seated upon the seat 20, Figure 2. In all other open or partly open positions of the valve stem 15, the inner end of the pin 50 rides upon the outside diameter or periphery of the screw-thread on the valve stem 15, as shown in Figure 1.

In use, the valve stem 15 is operated by the handle, not shown, in the usual manner, for turning the spigot off and on. When the discharge extension 31 is directed downwardly, Figure 1, the spigot serves the usual purposes for washing the hands or the like. When the discharge extension 31 is directed upwardly, shown dotted in Figure 1, the spigot serves as a convenient drinking fountain, the use of which will eliminate the necessity for glasses, cups and the like in bathrooms, train compartments, public lavatories and the like.

When the valve stem 15 is completely closed, Figure 2, and the spigot is accordingly fully shut off, the detent or notch 53 registers with the reduced bore 49 and may receive the inner end of the pin 50. The spout or nozzle 30 may now be turned upon its longitudinal axis, together with the bearing sleeve 35, and when this occurs, the pin 50 will be shifted axially into the notch or detent 53 when the outer end of the pin rides over the central, shallow portion 46 of the groove 45. This condition is illustrated in Figure 2, wherein the extension 31 has been rotated 90° from its upward or downward position. Thus, when the spigot is completely shut off, Figure 2, and only when this condition exists, the spout 30 may be turned so that the discharge extension 31 may be directed either upwardly or downwardly, as desired. When the extension 31 is in either the upward or downward position, the outer end of the pin 50 will be engaged in one of the relatively deep ends 47 of the groove 45, and the spring 52 will accordingly shift the pin axially outwardly, so that the inner end of the pin disengages the detent or notch 53, Figure 1. When this occurs, the valve stem 15 of the spigot may be rotated for turning on the spigot to the desired adjusted position. It is thus seen that the spigot may be turned on only when the discharge extension 31 of the nozzle 30 is directed either downwardly or upwardly. In any partially open or fully open position of the valve stem 15, the inner end of the pin 50 rides upon the periphery or outside diameter of the valve stem screw, as shown.

My spigot is highly simplified, compact and very easy to manipulate. The spigot is well adapted for all conventional usages, and the drinking fountain feature provided by it is highly advantageous and sanitary. From the outside my spigot presents the appearance of any other conventional lavatory spigot or the like.

It is to be understood that the form of the invention herewith shown and described is to be taken as a preferred example of the same, and that various changes in shape, size and arrangement of parts may be resorted to without departing from the spirit of the invention or the scope of the subjoined claims.

Having thus described my invention, I claim:

1. A fountain spigot comprising a valve body having an internal chamber provided with a valve seat, an adjustable valve element mounted

upon the valve body and shiftable toward and from the valve seat for opening and closing the spigot, the valve element having a locking detent, a spout having swiveled connection with the valve body and having a bore in communication with the chamber of the valve body, and means including a spring pressed pin mounted upon the valve body and connected with the spout for preventing the turning of the spout while the valve element is unseated, the spout being provided with means for projecting the spring pressed pin into the locking detent of the valve element when such element engages the valve seat and the spout is turned.

2. A fountain spigot comprising a valve body having an internal chamber provided with a valve seat, an adjustable valve stem mounted upon the valve body and shiftable toward and away from the valve seat for opening and closing the spigot, said valve element being provided with a locking notch, a bearing sleeve rotatably mounted upon the valve body and having a bore in communication with the chamber of the valve body, a spout carried by the bearing sleeve and including a discharge extension which may be directed either upwardly or downwardly, the bearing sleeve being provided in its inner end with an arcuate groove, the arcuate groove being relatively deep at its opposite ends and relatively shallow near its longitudinal center, the valve body being provided adjacent to the arcuate groove with a recess, and a spring pressed pin mounted within the recess and projecting into the arcuate groove and biased into engagement therewith, the pin being engageable in the locking notch of the valve element when the valve element engages the valve seat only, whereby the bearing sleeve and spout may be turned to engage the pin with the shallow portion of the groove only when the spigot is closed.

3. A fountain spigot comprising a valve body having an internal chamber provided with a valve seat, an adjustable valve stem mounted upon the valve body and shiftable toward and away from the valve seat for opening and clos-

ing the spigot, the valve body including a laterally extending, internally screw-threaded boss, a screw-threaded ring mounted within the internally screw-threaded boss, an annular lubricating seal mounted within the bore of the ring, a rotatable bearing sleeve mounted within the bore of the lubricating seal and having a bore in communication with the chamber and projecting axially beyond the ring and boss, the bearing sleeve being externally screw-threaded beyond the boss, a tubular spout mounted upon the screw-threaded portion of the bearing sleeve for rotation therewith, the inner end of the bearing sleeve being provided with an arcuate groove which is relatively shallow near its longitudinal center and relatively deep near its opposite ends, the valve body being provided with a recess leading into the arcuate groove, the valve element being provided in its periphery with a locking notch, said locking notch registering with the recess of the valve body only when the valve element engages the valve seat, and an axially shiftable spring pressed pin mounted within the recess of the valve body and extending into the arcuate groove and biased into engagement with the groove, the pin extending into one of the deep portions of the groove and locking the bearing sleeve and spout against rotation in all unseated positions of the valve element, the pin being displaced by the shallow portion of the groove into engagement with the locking notch of the valve element to permit turning of the bearing sleeve and spout only when the valve element engages the valve seat.
